Primary Examiner — Charles Hanson(74) *Attorney, Agent, or Firm* — Stephen J. Weyer, Esq.; Stites & Harbison, PLLC**CLAIM**

The ornamental design for an stroller shade, as shown and described.

DESCRIPTION

FIG. 1 is a perspective view taken from the front, right side and top side of the stroller shade of the present design.

FIG. 2 is another perspective view taken from the front, left side and top side of the stroller shade of FIG. 1, shown with panel rolled up in accordance with the present design; and, FIG. 3 is a different perspective view taken from the front, left side and top side of the stroller shade of FIG. 1, shown completely rolled up and attached to a stroller, in accordance with the present design.

The broken line showing of the stroller is included for the purpose of illustrating environment and forms no part of the claimed design.
